UNITED STATES PATENT OFFICE.

GEORGE D. HARDER, OF COBLESKILL, NEW YORK.

SILO.

SPECIFICATION forming part of Letters Patent No. 653,474, dated July 10, 1900.

Application filed May 29, 1900. Serial No. 18,437. (No model.)

To all whom it may concern:

Be it known that I, GEORGE D. HARDER, a citizen of the United States, residing at Cobleskill, Schoharie county, New York, have invented certain new and useful Improvements in Silos, of which the following is a specification.

My invention relates to silos, and is an improvement upon the invention described in Letters Patent of the United States granted to me on the 27th day of June, 1899, No. 627,732. The silo therein described, which is round and comprises a series of vertical staves held together by iron hoops, has in its walls, extending throughout the length thereof, an opening through which the ensilage is discharged. This opening is closed by a series of removable door-sections which slide in guideways provided by reinforcing-pieces overhanging the outer edges of the opening and overhanging pieces at the inner edges of the opening. The hoops or bands in the form of silo which has been patented to me run beneath the reinforcing-strips and find bearings at the outer edge of the wall of each opening. In the present improvement I have constructed the brace-pieces, which extend between the edges of the opening in the silo, with guides for the hoops, which serve to hold the parts of the hoops which span the opening away from the door-sections. The invention therefore includes means for guiding the hoops at each side of the opening in the silo, and it further includes the construction of the brace-piece, which may provide such guides.

The invention is illustrated in the accompanying drawings, in which—

Figure 1 is a detail elevation showing one brace spanning the opening in the silo. Fig. 2 is a detail plan view, parts being shown in section.

In the drawings but a section of the front part of the silo is shown. The vertical staves of which the body of the silo is constructed are shown at 1, the opening in the silo through which the ensilage is discharged at 2, and the reinforcing-strips at each edge of the opening at 3. The door-sections 4 are guided, as in my former case, in ways 5, formed between the overhanging portions of these strips and

the backing-strips 6. Brace-pieces span the opening 2 at intervals, which are provided with shoulder portions 7, abutting the edges of the reinforcing-pieces 3. The main portions 8 of the braces are intended to provide steps or rungs by which a person may ascend the silo to enter the same at any point. In the construction shown herein the shoulder portions of each brace are provided with depending portions 9, provided with guiding openings 10, through which the hoops 11, which encircle the silo, are guided. As shown herein, each reinforcing-strip is provided with an opening 12 in line with the opening 10 in the abutting portion 9, which provides a guide for the hoop; but dependence is not placed on these openings 12 in the strips 3 to hold the part of the hoop spanning the opening 2 away from the door-sections. The brace-pieces, however, being heavy castings, the openings 10, provided therein, serve this purpose admirably.

It will be understood that the brace-pieces may be made of any suitable material. It will also be seen that by elongating the ends of the brace-pieces, as at 9, either above or below or on both sides of the line of the main portion 8 a longer bearing is provided against the shoulders of the reinforce-pieces.

I claim—

1. The combination with a round silo having an opening in the wall thereof, hoops encircling the silo and spanning said opening, and a sectional door closing the opening, of means for guiding the hoops at each side of said opening to hold the spanning portions of said hoops away from the door-sections, substantially as described.

2. The combination with a round silo having an opening in the wall thereof extending throughout the length of the same and hoops encircling said silo and spanning the opening, of braces extending between the edges of said opening, said braces providing guides for said hoops, substantially as described.

3. The combination with a round silo having an opening in the wall thereof extending throughout the length of the same, reinforcing-strips overhanging the edges of said opening, door-sections for closing the opening, a

brace-bar spanning said opening having shoulder portions abutting the strips, hoops encircling the silo and spanning said opening, and depending portions integral with the 5 braces having guide-openings through the same for the hoops, substantially as described.

In testimony whereof I affix my signature in presence of two witnesses.

GEORGE D. HARDER.

Witnesses:

SANFORD S. MYERS,
ESTELLE M. TIDD.
